TELEVISION SCREEN UNIT

Richard J. Whipple, Abington, Pa., assignor to Philco Corporation, Philadelphia, Pa., a corporation of Pennsylvania

Application July 8, 1958, Serial No. 51,696

Term of patent 14 years

(Cl. D56—4)

FIG. 1.

FIG. 2.

FIG. 3.

Figure 1 is a side elevational view of a television screen unit, showing my new design;

Figure 2 is a rear elevational view; and

Figure 3 is a front perspective view thereof.

The side not shown is substantially the same in appearance as the side shown. The dominant features of the design reside in the portions shown in full lines.

I claim:

The ornamental design for a television screen unit, substantially as shown and described.
